SAC FILLING MACHINE

Max Knobel, Arlington, Mass., assignor to W. A.
Sheaffer Pen Co., Fort Madison, Iowa, a corpora-
tion of Delaware

Application January 16, 1947, Serial No. 722,455

4 Claims. (Cl. 226—63)

1

This invention relates to an apparatus for filling a container with a viscous fluid without entrapment of air bubbles therein. More particularly it has to do with the filling of a flexible sac with a viscous writing fluid, for example, a sac and fluid adaptable for use with a so-called ball-point writing instrument.

Ball-point pens now available generally employ a writing tip in the form of a sphere of approximately one millimeter diameter mounted for universal rotation in a socket having an ink passage therethrough, the passage being in fluid communication with an ink reservoir. For use in a pen of the ball-point type, a viscous ink, somewhat in the nature of printing ink, is required, and in order to obtain uniform, uninterrupted flow of ink to the ball, it is essential that no air bubbles be present in the body of ink in the reservoir or the passages intermediate the reservoir and that part of the socket whereto the ink adheres to the ball for transfer to the writing surface. Even a minute air bubble can interfere with the ink flow and cause a skip or faintness in the written line.

One type of sac found preferable for use as a reservoir in a ball-point pen may comprise soft rubber, nylon or other materials capable of lending a flexible or flaccid characteristic to the sac, whereby gradual reduction in the ink supply will permit collapse of the wall of the sac and assist in feeding of the ink therefrom. A sac of this type is generally mounted on a metallic or other nozzle part having means for securement into that portion of the pen in which the writing ball is mounted, and the nozzle part is provided with a small passage through which the ink may issue. Due to the flaccid nature of the sac, it is impracticable to attempt to fill the sac proper with ink, and then to mount the same on the nozzle part, not only for the reason that an air space will be left in the nozzle part, but because the handling of the filled sac as an entity is difficult and messy. Heretofore the filling operation has been by means of an implement in the nature of a hypodermic needle which is difficult to handle, and, due to the viscous nature of the fluid, extremely slow. Moreover, the inclusion of air bubbles is practically unavoidable. Even that method by which the open end of the filling conduit, e. g., a hypodermic needle, is first inserted to the bottom of the sac and then gradually withdrawn as the liquid level rises, fails to yield a bubble-free supply. The theory of this latter operation is that the air is ejected by the rising liquid level. However, in order for this object to be accom-

2

plished without wastage of ink, the needle should be withdrawn at exactly the same rate that the sac is filled, otherwise the tacky ink adhering to the needle is wasted, and the same must be wiped before starting to fill the succeeding sac. If the needle is withdrawn too fast and the stream of ink falls through air before becoming part of the body of ink in the partially filled sac, there is almost a certainty that some air bubbles will be entrapped. It is almost impossible to adjust the rate of withdrawal of the needle to exactly equal the rate at which the sac is filled because not only is it impossible to maintain constant flow from the needle but the sacs vary considerably in internal cross section.

The present invention contemplates, as certain of its principal objects, a method of filling the sac and the provision of an apparatus for accomplishing the operations involved in a rapid, semi-automatic manner resulting in a substantial increase in production over processes and equipment now employed. Such method as herein to be described briefly comprises a complete evacuation of the sac and the rigid nozzle part to which the sac is secured, then the filling of the sac under pressure and under conditions rendering the inclusion of air bubbles practically impossible, and then the suctioning of a predetermined small quantity of the ink from the sac to prevent overflow thereof under circumstances to be noted. For convenience in what follows, the flexible sac and nozzle assembly will be referred to as the "sac section."

Another object is to provide apparatus for accomplishing the several steps aforesaid in a clean, economical manner by utilizing a valve operable through several phases to perform the steps in required sequence, and by the allocation to each step of time sufficient to insure efficient carrying out of each part of the cycle.

Still another object is the provision of apparatus as aforesaid including a supply of ink and means for feeding the ink through the valve and to the sac section under carefully controlled pressure conditions.

A further object is to provide a sac-filling apparatus utilizing a novel form of holder for the sac section whereby loading of the section in operative relation to the apparatus is greatly facilitated.

An additional object resides in providing apparatus for the purpose stated which includes rapidly operable means for receiving the holder aforesaid to maintain the inlet of the sac section 55 in filling position.

Other objects will become apparent as the description proceeds.

In carrying out my invention in one form I provide a reservoir for storing a substantial supply of ink and associated pressure means for insuring and maintaining a predetermined outflow of ink from the reservoir to a valve. Such valve is preferably of the rotary plug type, and is provided with a connection to a source of vacuum for evacuation of air or withdrawal of ink from the sac. By providing passages of novel form in the valve and means for rotating the movable part of the valve through a cycle, the several steps of the process are expeditiously performed in a clean and uniform manner. The apparatus is motor-driven, and manually controlled for each successive sac handled thereby.

In the drawings which show a preferred embodiment of the invention:

Fig. 1 shows a front elevational view of the apparatus;

Fig. 2 is a plan view, partly in section, of the apparatus of Fig. 1;

Fig. 3 is a detail view partially in cross section to show the reservoir and means for applying pressure to the ink supply;

Fig. 4 is a detail in perspective of the rotary plug member of the valve;

Fig. 5 is a front elevational detail of the valve with certain parts sectioned;

Fig. 6 is a cross-sectional view taken on the line 6—6 of Fig. 2;

Fig. 7 is a plan view in detail of the sac holder carriage;

Fig. 8 is a cross-sectional view taken on the line 8—8 of Fig. 2;

Fig. 9 is a cross-sectional view taken on the line 9—9 of Fig. 2;

Fig. 10 is a cross-sectional view taken on the line 10—10 of Fig. 2; and

Figs. 11a, 11b, 11c, 11d and 11e are diagrams representing the functions of the cycling valve.

By way of exemplification, that form of the apparatus of the invention to be herein described is adapted to charge a sac section of the kind illustrated in Fig. 10, the same comprising a sac 10 of flaccid material such as latex or nylon which sac may be of any cross section, secured to a metallic nozzle-like part 11 by contraction of the sac about a neck 12 of the nozzle and banded by means (not shown) to insure thorough engagement. Nozzle 11 has an axial aperture 13 therethrough for passage of the ink from the sac to the tip of the pen and is moreover chamfered at 14 for interfitting with other parts of the pen not pertinent here, but which permits suitable loading of the sac section with respect to the ink outlet of the filling apparatus.

Due to the flexible or flaccid construction of the sac 10, I have found it preferable to carry the sac section in a holder 16 (Figs. 2 and 10) comprising an open-ended tubular body 17 slit at one end at several spaced apart points 18 about its circumference, the metal therebetween thus being rendered easily bendable to form a plurality of clamping fingers 19 adapted to grip the nozzle 11, a shoulder 22 thereof abutting the ends of the fingers to fix the axial location of the sac section relatively to the holder 16. To provide or to release clamping pressure of the fingers 19, a sleeve 23 having a knurled periphery is arranged for sliding movement on the body 17. It is desirable to be able to view the sac as it is being filled, and for that purpose an elongated opening 24 is provided in the holder 16. 75

Now referring to Figs. 1 and 2, the apparatus comprises a base 31 having platforms 32 and 33 defining a depressed base portion 34. To secure the machine to its support, a plurality of apertures 30 may be provided, the latter being in flanges 36 and 37 forming extensions of the base 31. Supported by posts 35 (Fig. 3) on platform 32 is a reservoir 41 having a screwed filling cap 42 into which a nipple 43 is secured, a T 44 being then connected thereto. Into one outlet of T 44 a needle valve 45 is tapped, the other side of the valve being in communication with a source of air pressure, and into the other outlet of the T, a tube 46 is connected, the opposite end of the tube extending downwardly into a vessel 47, e. g., a test tube.

Vessel 47 is partially filled with a heavy fluid, preferably mercury, indicated at 51, and serves as a pressure regulator. The lower open end of tube 46 lies beneath the level of the mercury whereby air in reservoir 41 and tube 46 is therefore restrained from escaping through the end of the tube by the presence of the mercury. It will be apparent, however, that if the air pressure in the reservoir exceeds a certain value the air will force the mercury out of the lower end of tube 47 and will bubble up through the mercury and escape. This will relieve the air pressure in the reservoir and maintain it at a definite value. A casing 52 having a base 53 supports the vessel 47 and the vessel and casing assembly is rendered vertically adjustable by providing a threaded stud 54 carried in an aperture 55 in the platform 32. Lock nuts 56—56 are provided for obvious reasons. To provide fluid communication between the reservoir 41 and the valve shortly to be described there is provided an elbow 57 and coupling 58.

In accordance with the invention, the sac is first evacuated, then filled, and subsequently a small portion of the contents suctioned off. Desirably, I perform these functions in a timed, sequential manner by means of a rotary valve. Turning to Figs. 2, 4, 5 and 8, the valve block or casing 61 is mounted on the platform 32 by screws (not shown) taking into apertures 62—62, and includes an ink inlet port 63 receiving the coupling 58. Substantially at the longitudinal mid-axis of the block 61 is positioned a rotary valve member or plug 65, the same being preferably of frusto-conical form to insure a constant snug fit into the mating aperture 66. Plug 65 is provided with an extension 67 for connection with driving mechanism to be described, and the aperture 66 is made slightly longer than the corresponding tapered part of the plug 65 to permit axial adjustment of the latter to accommodate wear.

Valve plug 65, best seen in Fig. 4, includes a plurality of channels or passages as follows: 71, traversing the entire periphery and in alignment axially with port 63; 72 extending, in this embodiment, over 231° of the periphery and in alignment with the ink outlet port 77, and provided with three axially extending branches 73, 74 and 75 all in communication with channel 71; 76 extending axially from the inner end of the plug to the ink outlet port 77; and 78 also extending axially from the inner end of the plug end terminating beyond the port 77.

Coaxially in alignment with the plug 65 is a suction aperture 62 to which is fitted a coupling 83 in turn receiving a pair of separating vessels 84—84, a vacuum pump 85 being connected to nozzle 85a.

To support the holder 16 and its therein clamped sac section there is provided a carriage 88 in the form of an elongated parallelepiped slidably supported on a block 89 secured to the platform 32 (Figs. 2, 7 and 10). Carriage 88 is disposed with a diagonal of an end face in a horizontal plane and gibs 91-91 bearing on the sloped upper sides of the carriage 88 retain the latter in sliding relation with the block 89; the sloped lower sides 92-92 slidably engaging correspondingly shaped portions of the block 89. Projecting upwardly from the carriage 88 is a pair of integral saddles 93 and 94 each having a substantially semi-cylindrical channel at the top thereof, the channels associated with the saddles 93 and 94 having radii corresponding to the body 17 and sleeve 23 respectively of the sac section holder 16. Accordingly when the holder is positioned operatively with respect to the port 77 in a manner to be described, the saddles 93 and 94 provide lateral guiding, and the front face of the saddle 93, being in abutment with the sleeve 23, may force the nozzle 11 into tight engagement with the port while simultaneously assisting in maintaining the grip of the sleeve 23 on the fingers 19. The holder 16, carriage 88 and block 89 may be said to constitute a jig for supporting the sac section in operative relation with the apparatus.

In order to maintain the carriage 88 rearwardly in Fig. 2, or to the right in Fig. 10, there is provided a compression spring 97 supported on a pilot screw 98 entering an aperture 99 in the carriage, the screw being threadedly engaged in a plate 101 secured to the front face of the block 89. Forward retraction of the carriage is effected by a handle 104 pivoted on a shoulder screw 105 mounted on the platform 32, the inner end of the handle being circular in outline and engaged in a slot 106 in the carriage, the handle clearing the block 89 through a slot 107.

To provide a snug, leakproof connection between the port 77 and nozzle 11, there is (Figs. 2 and 5) a washer 111 of yieldable material, e. g., neoprene, a form of synthetic rubber, supported by a metal washer 112 screwed to the front face of the valve block 61, the hole of the washer 111 being of such size as to receive the chamfered end 14 of the nozzle 11 in a wedged fit, the spring 97 affording the requisite pressure to that end.

For use in ball-point writing instruments of the kind herein referred to, a paste-like ink is preferred. Being viscous, it may be more accurately controlled and more easily passed through the various conduits, and particularly the valve of the apparatus, if rendered more fluid. Accordingly, I find it advantageous to provide means to heat the valve and thus to render the ink more fluid thereabout and therein. Such means preferably comprises an electric heating element 115 of any suitable type (Fig. 5) inserted in a hole 116 in the valve body 61, and retained by a set-screw 117. An additional aperture 118 may be provided coaxially with the hole 116 to receive a prod for pushing the element 115 from its receptacle when removal is desired. To indicate the operating temperature of the valve, the bulb of a conventional thermometer 119 (Fig. 1) may be inserted in an aperture 121 (Figs. 5 and 6) in the valve body 61. Moreover, by means of a suitable rheostat, the temperature of the element 115 may be varied to obtain optimum viscosity of the ink. A thermostat (not shown) of any usual type may be connected in the circuit including the element 115 to regulate the temperature thereof. A conveniently placed lamp

123 (Fig. 1) may be provided to indicate in a conventional manner whether or not the element is receiving current. The main current-interrupting switch is shown at 125, and a lamp 120 may be included to show whether the switch 125 is on or off.

Valve rotor 65 is arranged to turn through one revolution to perform the cycle involved in filling one sac, and is therefore arranged to be rotated through a uni-revolutional clutch and motor drive. Referring to Figs. 1, 2, 8 and 9, an electric motor (not shown) is connected through a belt 126 and pulley 127 to the shaft 128 supported on bearings 129-129 secured to the platform 33. A pinion 132 affixed to shaft 128 drives a gear 133 keyed to the stub shaft 134 supported in a bearing 135 carried on posts 136, the latter resting on the flanges of the underneath bearing 129, and screws 137 being employed to fasten both the upper and lower bearings to the platform 33. A stop collar 141, together with the hub of gear 133, retains the shaft 134 axially, the latter being enlarged at its inner end and apertured to form a cup 142 in which the stem 67 of the valve rotor 65 is freely rotatable. Arranged for rotation relatively to the shaft 134 is a disc 143 having a notch 144 in its periphery and a rigid pin 145 extending axially therefrom and adjacent the periphery of the cup 142. Juxtaposed against the right end face of the valve block 61 is a collar 146 affixed by a set screw to the stem 67. A rigid pin 147 projects from the outer face of the collar 146 in radial alignment with pin 145, the ends of the two pins being overlapped as seen best in Fig. 9. A coiled torsion spring 149 closely surrounds the portion 142 and each looped end thereof is retained about pins 145 and 147. Adapted to cooperate with the disc 143 is a trip lever 152 including a forward thumb piece 153 and an integral dog 154 having a sloped tip for engagement with the notch 144. Lever 152 is pivoted on a post 155 affixed to the base portion 34 and is guided in a slot 156 in a second post 157. A compression spring 158 seated in the post 157 urges the lever 152 upwardly to maintain the dog 154 normally into locking engagement with the notch 144.

Operation of the apparatus is as follows: The reservoir 41 is completely or partially filled with a supply of ink through the open end normally closed by the screw cap 42. By means of the valve 45, compressed air from any suitable source is supplied to the reservoir 41. If desired, a regulator may be installed in the compressed air line for maintaining the pressure at a predetermined value, and the flow may be further throttled through the needle valve. Only a few ounces of air pressure has been found sufficient to provide the small additional pressure in excess of the head of ink in the reservoir necessary to maintain flow of the ink to and through the cycling valve. The rate at which the air is bled through the needle valve is very slight and the pressure on the surface of the ink in the reservoir is, therefore, very closely equal to the pressure corresponding to a column of mercury equal to the distance from the lower open end of the tube 46 immersed in the mercury 51 to the top surface of the mercury. That is to say, the space above the ink is virtually a dead space, because the rate at which the ink leaves the reservoir is negligible. The pressure on the ink is determined essentially by the column of mercury described and does not depend to any substantial extent on the incoming air pressure. It will be understood that the

regulator ahead of the needle valve just referred to may be, for example, of the conventional diaphragm type having requisite sensitivity at low pressures and the additional means including the column of mercury dispensed with.

Ink enters the cycling valve body 61 through port 63 and fills the recess 71 wherefrom it is channeled through paths now to be described. At stopped position of the uni-revolutional clutch, the parts are as shown in Fig. 2. An empty sac section is loaded into the holder 16 in the manner heretofore detailed (Fig. 10), and the charged holder deposited on the carriage 88 in the position indicated. At the time of loading, the handle 104 has been manually operated to slide the carriage forwardly in Fig. 2, or to the left in Fig. 19, against the bias of the spring 97 so that after loading the holder on the carriage and releasing the handle, the nozzle 11 is moved against the washer 111 and there firmly held by the spring 97.

Following the operation aforesaid, the thumb piece 153 is depressed and dog 154 thus withdrawn from engagement with the notch 144. Spring 149 is of such dimensions that its normally coiled state will cause it to grip the portion 142. Thus when disc 143 is locked against rotation by dog 154 the spring is uncoiled slightly and slippage may occur between the same and cup 142. However, when the dog 154 is released from the disc 143, the spring may resume its smaller diameter to grip the cup 142. Consequently the cup and spring may rotate together and the collar 146, to which the inner end of the spring is secured, may, together with the rotor 65, also rotate. Inasmuch as lever 152 is released immediately following tripping of the clutch, the dog 154 is free to enter the notch 144 under urging of spring 153, and upon said dog rotating to the locked position one revolution of the clutch has been completed and the valve rotor is in stopped position as shown. Pins 145 and 147 are in overlapped relation, as stated, and insure proper angular positioning between disc 143 and rotor 65.

The various functional phases of rotor 65 are brought out in Figs. 11a through 11e, the several pertinent parts of the valve there shown bearing the same reference characters as in Figs. 2 and 4. In stopped position, the rotor and valve block are as shown in Fig. 11a and none of the passages of the rotor is in communication with outlet port 71. Upon rotation of the rotor passage 78 (Fig. 11b) is brought into register with port 77 and communication provided from sac 10, through port 77, channel 78, port 32, and separators 84 to vacuum pump 85 and the air in the sac is exhausted.

Continued rotation of the rotor carries the beginning of channel 72 into register with port 77 and communication is provided between the exhausted sac and recess 71 containing ink, and the sac begins to fill. During further rotation corresponding to the peripheral length of channel 72 the latter continues in register with port 77 until the sac is completely filled. It will be noted that passage 72 receives ink from recess 71 through three cross passages 73, 74 and 75 in order to insure adequate ink flow all during that portion of the cycle.

The practically complete evacuation of the sac section before filling makes it possible to fill the section substantially completely by first filling the open end of the section and finally filling the closed end, the direct reverse of the needle

method heretofore alluded to. For all practical purposes the evacuation of the sac is complete, but should the machine not function ideally, then any small amount of air still present is at very low pressure, and this will all be forced ahead of the incoming ink and become evident as a tiny air bubble at the closed end of the sac, and at a place farthest from the writing point. Such small air bubbles in this position have never caused any difficulty.

Further rotation of the rotor cuts off the supply of ink to the sac and carries channel 76 into register with port 77 to connect the sac once more to vacuum and a portion of the ink is therefore sucked from the sac.

Since the ink is forced into the sac under slight pressure there is a tendency, with sacs of certain materials, e. g., rubber, for the sac to become slightly distended beyond its normal dimensions, and accordingly the withdrawal of a small amount of ink after complete filling is a desirable step. On the other hand a sac of nylon, i. e., polyexamethylene adipamide, being substantially non-distensible, would not fall in the aforesaid classification and a successful operation could be accomplished without the final suctioning step.

If the sac were stretched before or during the screwing of the sac section into the writing tip, the sac section being open and the ink being under pressure, a certain amount of ink would flow out, making a messy operation. Furthermore, if under the foregoing conditions the sac section were placed in its protective casing and a usual form of spring and pressure bar inserted between the casing and sac, the bias of this spring added to the distended sac would cause too heavy an ink flow and weeping from the writing point when the pen is not in use. Accordingly the withdrawal of a slight amount of ink from the filled sac, is, under most circumstances, to be preferred.

Since final suctioning of part of the ink from the sac carries the ink into the vacuum line, the separators 84-84, comprising simple vessels open to the line, are provided to receive the ink caught in the line and prevent the same from being carried back to the vacuum pump 85. This final suctioning action serves another important purpose by drawing away from the port 77 some of the ink therein, thereby avoiding dripping and consequent waste of ink. To catch any drippings from the port 77, I provide thereunder a container 150 (Fig. 2), the valve block 61 being recessed at 60 on its front face (Fig. 6) to receive one side of the container and to insure that any drippings reach the interior of the container.

The time found best for one cycle of operation and for filling a sac having an internal diameter of 0.195" and internal length of 2.375" is five seconds, this period being subdivided as indicated in Fig. 11a, wherein the preferred angular spacing of the air exhausting channel 78, the filling channel 72 and the ink suctioning channel 76 is as shown.

For storing a supply of loaded or unloaded extra holders 16, a plurality of apertures 149 (Fig. 2) may be provided in the platform 33, and the same used in an obvious manner.

When filling a sac by a needle, the operation is necessarily slow since at high velocity the thin wall of the sac might be ruptured, and air present in the sac might be aspirated into the stream of ink filling it. In contrast, the filling operation as performed by my apparatus is substantially

accelerated, and without the dangers inherent in the needle method.

While I have shown particular embodiments of my invention, it will be understood, of course, that I do not wish to be limited thereto since many modifications may be made, and I therefore contemplate by the appended claims to cover any such modifications as fall within the true spirit and scope of my invention.

I Having thus described my invention, what I claim and desire to secure by Letters Patent is:

1. Apparatus for filling a container with fluid material comprising in combination a source of vacuum, a source of fluid material supply, a rotary valve, conduits interconnecting each of said sources with said valve, said valve having a port to which the container is adapted to be connected, and power-driven means for rotating said valve to interconnect said sources singly and in a predetermined sequence to said port, said power-driven means including a uni-revolutional clutch for actuating said valve from rest through one revolution.

2. Apparatus for filling a container with a viscous fluid comprising in combination a valve including a rotary member, said valve having a fluid inlet, a fluid outlet and a vacuum connection, a source of supply of fluid in communication with said inlet, a vacuum pump in communication with said vacuum connection, said rotary member having a plurality of channels so constructed and arranged that upon rotation of said member said fluid outlet is successively placed in fluid communication with said pump a first time, said fluid source and said pump a second time in the order recited for one cycle of operation of the apparatus, a source of power for rotating said valve member, a uni-revolutional clutch intermediate said source of power and member for rotating said member through one cycle, and manual means for releasing said clutch for performance of a cycle of operation.

3. Apparatus for filling a container with a fluid

comprising in combination a valve having a fluid inlet and a fluid outlet, a reservoir for holding a supply of fluid, and a conduit between said reservoir and inlet, and means for maintaining slightly superatmospheric pressure on the body of fluid in the reservoir for insuring positive flow of fluid from said reservoir to and through said valve, said means including a vessel containing a liquid of relatively heavy density and a tube having one open end thereof immersed in said liquid and the other end in communication with the space in the reservoir above the level of the fluid therein.

4. Apparatus for filling a container with a viscous fluid comprising in combination a valve having a fluid inlet and a fluid outlet, a reservoir for holding a supply of fluid and a conduit between said reservoir and inlet, and means for maintaining slightly superatmospheric pressure on the body of fluid in the reservoir for insuring positive flow of fluid from said reservoir to said valve, said means including a vessel containing liquid of relatively heavy density, a tube having one open end thereof immersed in said liquid and the other end in communication with the space in the reservoir above the level of fluid therein, said vessel being shiftable with respect to the open end of the tube therein to vary the effective head of liquid above said open end.

MAX KNOBEL.
